Primary Examiner — Stacia Cadmus(74) *Attorney, Agent, or Firm* — Tarolli, Sundheim, Covell & Tummino LLP; John A. Yirga, Esq.(57) **CLAIM**

The ornamental design for a vehicle wheel rim, as shown and described.

DESCRIPTION

FIG. 1 is a perspective view of a vehicle wheel rim in accordance with the present disclosure; and, FIG. 2 is a front elevation view thereof.

The broken lines showing an unclaimed portion of the vehicle wheel rim is included for the purpose of illustrating environment and forms no part of the claimed design.
